UNITED STATES PATENT OFFICE.

WILLIAM B. JACKSON AND WILLIAM BURNETT, OF ELLINWOOD, KANSAS.

SCREW.

No. 863,188.

Specification of Letters Patent.

Patented Aug. 13, 1907.

Application filed November 16, 1906. Serial No. 343,752.

To all whom it may concern:

Be it known that we, WILLIAM B. JACKSON and WILLIAM BURNETT, citizens of the United States, residing at Ellinwood, in the county of Barton and State of 5 Kansas, have invented certain new and useful Improvements in Screws, of which the following is a specification.

The object of our invention is to provide an improved construction of screw in which means are provided to 10 lock the screw in place and prevent its accidental withdrawal.

The invention consists in certain constructions and arrangements of the parts of the screw adapted to be locked in place, all as will be hereinafter fully described 15 and claimed.

For a full understanding of the invention and the merits thereof and also to acquire a knowledge of the details of construction of the means for effecting the result, reference is to be had to the following description and accompanying drawings, in which:

Figure 1 is a longitudinal sectional view of one form of screw in which the invention may be embodied; and, Fig. 2 is a perspective view, partially in section, of another form of screw to which the invention may be applied.

Corresponding and like parts are referred to in the following description and indicated in all the views of the drawings by the same reference characters.

Referring to the drawings, the numeral 1 designates 30 a screw which is provided with a head 2 for the application of a wrench or the like and the said screw is also provided with a central longitudinal bore 3, extending downwardly from the head and preferably extending to the point where the threads begin, as illustrated in 35 the drawings. At the bottom of the longitudinal bore 3, the body of the screw is formed with transverse openings 4 extending outwardly in opposite directions from the bore 3.

5 designates a key which is constructed of metal and 40 is provided with two integrally connected members 5^a that are initially in contact with each other throughout their length, the said key being initially of uniform thickness throughout and being designed to fit in the longitudinal bore 3. In the preferred construction, 45 the key 5 is constructed of a single piece of metal doubled upon itself at its middle to form the two members 5^a, and the ends of these members are first inserted in

the bore 3. Then, after the screw has been screwed into its place, one or two taps upon the head of the key 5 will result in the divergence of the two extremities 50 of the members 5^a in opposite directions out through the transverse openings 4 and into the wood or the like, so as to lock the screw securely in place.

As illustrated in Fig. 2, the screw 1^a is provided with a head 2^a having a transverse kerf or groove 6 for the 55 application of a screw driver. In this construction, the bore and transverse opening are similar to the bore and opening of the first described screw, but the key is initially of such a length that its head will lie within the margin of the bottom of the kerf 6, so as to interfere 60 in no wise with the proper use of the screw-driver to turn the screw. In order to unlock the screw, it is only necessary to drive the key downwardly until its head reaches the bottom of the bore 3, whereupon the head will split where it connects the two members 5^a together 65 and thereby allow the screw to be withdrawn.

From the foregoing description in connection with the accompanying drawing, it will be seen that we have provided a very simple construction of lock screw, in which the key is of uniform diameter throughout in 70 initial construction and may therefore be driven entirely down into the longitudinal bore 3 so as to lock the screw as above described. In the manufacture, these keys may be so made as to accompany each screw, and avoid the necessity of looking around for a key when it is 75 desired to practice the invention.

Having thus described the invention, what is claimed as new is:

As a new article of manufacture, the herein described screw provided with a head having a transverse kerf for 80 the reception of a screw driver and a longitudinal bore extending downwardly from the kerf and with a transverse opening leading downward in opposite directions from the bottom of the bore, and a key consisting of an integral piece of metal bent at its middle to produce two members 85 fitted within the bore with their extremities lowermost and diverging and lying wholly within the transverse openings, the opposite end of the said key lying below the bottom wall of the kerf for the purpose set forth.

In testimony whereof we affix our signatures in presence of two witnesses.

WILLIAM B. JACKSON. [L. S.]
WILLIAM BURNETT. [L. S.]
